Primary Examiner — Kelley Donnelly

(74) Attorney, Agent, or Firm — Jones Walker LLP

(57) **CLAIM**

I claim the ornamental design for an illuminated container for food or drink, as shown and described.

DESCRIPTION

FIG. 1 is a top, front perspective view of an illuminated container for food or drink;

FIG. 2 is a bottom plan view thereof;

FIG. 3 is a top plan view thereof;

FIG. 4 is a left side plan view thereof;

FIG. 5 is a right side plan view thereof;

FIG. 6 is a front plan view thereof; and,

FIG. 7 is a rear plan view thereof.

The dashed lines are for the purposes of illustrating radiating light and form no part of the claimed design.

1 Claim, 7 Drawing Sheets
